The ornamental design for a bicycle towing hitch, as shown and described.

DESCRIPTION

FIG. 1 is a left-side elevational view of a bicycle towing hitch, showing my new design;

FIG. 2 is an enlarged front perspective view thereof;

FIG. 3 is a rear perspective view of FIG. 2;

FIG. 4 is a top plan view of FIG. 2;

FIG. 5 is a bottom plan view of FIG. 2;

FIG. 6 is a front elevational view of FIG. 2;

FIG. 7 is a rear elevational view of FIG. 2;

FIG. 8 is a left-side elevational view of FIG. 2; and,

FIG. 9 is a right-side elevational view of FIG. 2.

The broken lines showing a portion of a bicycle in FIG. 1 depict environmental matter and form no part of the claimed design. The remaining broken lines show a portion of the towing hitch that forms no part of the claimed design.
